(57) **CLAIM**

The ornamental design for a helmet, as shown and described.

DESCRIPTION

FIG. 1 is a top perspective view of a helmet in an operational condition in accordance with a first embodiment of the present disclosure.

FIG. 2 is a bottom perspective view thereof.

FIG. 3 is a first side view thereof.

FIG. 4 is a second side view thereof.

FIG. 5 is a third side view thereof.

FIG. 6 is a fourth side view thereof.

FIG. 7 is a top view thereof.

FIG. 8 is a bottom view thereof.

FIG. 9 is a top perspective view of a helmet in a collapsed condition in accordance with the first embodiment of present disclosure.

FIG. 10 is a bottom perspective view thereof.

FIG. 11 is a first side view thereof.

FIG. 12 is a second side view thereof.

FIG. 13 is a third side view thereof.

FIG. 14 is a fourth side view thereof.

FIG. 15 is a top view thereof.

FIG. 16 is a bottom view thereof.

FIG. 17 is a top perspective view of a helmet in an operational condition in accordance with a second embodiment of the present disclosure.

FIG. 18 is a bottom perspective view thereof.

FIG. 19 is a first side view thereof.

FIG. 20 is a second side view thereof.

FIG. 21 is a third side view thereof.

FIG. 22 is a fourth side view thereof.

FIG. 23 is a top view thereof.

(Continued)

FIG. 24 is a bottom view thereof.

FIG. 25 is a top perspective view of a helmet in a collapsed condition in accordance with the third embodiment of the present disclosure.

FIG. 26 is a bottom perspective view thereof.

FIG. 27 is a first side view thereof.

FIG. 28 is a second side view thereof.

FIG. 29 is a third side view thereof.

FIG. 30 is a fourth side view thereof.

FIG. 31 is a top view thereof.

FIG. 32 is a bottom view thereof.

FIG. 33 is a top perspective view of a helmet in an operational condition in accordance with a fourth embodiment of the present disclosure.

FIG. 34 is a bottom perspective view thereof.

FIG. 35 is a first side view thereof.

FIG. 36 is a second side view thereof.

FIG. 37 is a third side view thereof.

FIG. 38 is a fourth side view thereof.

FIG. 39 is a top view thereof; and,

FIG. 40 is a bottom view thereof.

The broken lines in the figures illustrate the portions of the helmet that form no part of the claimed design.

1 Claim, 40 Drawing Sheets

Related U.S. Application Data

which is a continuation of application No. 29/593,908, filed on Feb. 14, 2017, now Pat. No. Des. 853,651, which is a continuation of application No. 29/582,807, filed on Oct. 31, 2016, now Pat. No. Des. 806,317.
